Patented Oct. 29. 1861.

Dec. 1485

Article No. 1485.   Caleb W. Palmer of Troy, N.Y.
Letters Patent No. 120. Dated Oct. 29, 1861.

The schedule referred to in these Letters Patent and making part of the same.

Des. 1485

To all whom it may concern.

Be it known that I, Caleb W. Palmer of the City of Troy, in the County of Rensselaer, and State of New York, have invented or produced a new and original design for Cooking Stoves, and I do hereby declare that the following is a full and exact description of the same, reference being had to the annexed photographic drawing of a cooking-stove having my said design.

The distinguishing characteristic of my said ornamental design for a cooking-stove is, the arrangement, on each of the side and end doors or panels A, B, C, and D, of a moulding *e*, along the border, and the variously proportioned and developed compound ornament, *f*, on the middle, of each of the said doors or panels, and the disposition of the ornament *g*, on the side plate *H*, as shown by the annexed drawing.

What I claim as new and of my invention or production and desire to secure by Letters Patent is, cooking-stove plates ornamented as above described.

Witnesses.
